(57) **CLAIM**

The ornamental design for a ball pit set, as shown and described.

DESCRIPTION

FIG. 1 is a front perspective view of the first part of the ball pit set thereof;

FIG. 2 is a bottom perspective view of the first part of the ball pit set thereof;

FIG. 3 is a front view of the first part of the ball pit set thereof;

FIG. 4 is a rear view of the first part of the ball pit set thereof;

FIG. 5 is a left side view of the first part of the ball pit set thereof;

FIG. 6 is a right side view of the first part of the ball pit set thereof;

FIG. 7 is a top view of the first part of the ball pit set thereof;

FIG. 8 is a bottom view of the first part of the ball pit set thereof;

FIG. 9 is a front perspective view of the second part of the ball pit set thereof;

FIG. 10 is a bottom perspective view of the second part of the ball pit set thereof;

FIG. 11 is a front view of the second part of the ball pit set thereof;

FIG. 12 is a rear view of the second part of the ball pit set thereof;

FIG. 13 is a left side view of the second part of the ball pit set thereof;

FIG. 14 is a right side view of the second part of the ball pit set thereof;

FIG. 15 is a top view of the second part of the ball pit set thereof;

FIG. 16 is a bottom view of the second part of the ball pit set thereof;

FIG. 17 is a front perspective view of the third part of the ball pit set thereof;

FIG. 18 is a bottom perspective view of the third part of the ball pit set thereof;

FIG. 19 is a front view of the third part of the ball pit set thereof;

FIG. 20 is a rear view of the third part of the ball pit set thereof;

FIG. 21 is a left side view of the third part of the ball pit set thereof;

(Continued)

FIG. 22 is a right side view of the third part of the ball pit set thereof;
 FIG. 23 is a top view of the third part of the ball pit set thereof;
 FIG. 24 is a bottom view of the third part of the ball pit set thereof;
 FIG. 25 is a front perspective view of the fourth part of the ball pit set thereof;
 FIG. 26 is a bottom perspective view of the fourth part of the ball pit set thereof;
 FIG. 27 is a front view of the fourth part of the ball pit set thereof;
 FIG. 28 is a rear view of the fourth part of the ball pit set thereof;
 FIG. 29 is a left side view of the fourth part of the ball pit set thereof;
 FIG. 30 is a right side view of the fourth part of the ball pit set thereof;
 FIG. 31 is a top view of the fourth part of the ball pit set thereof;
 FIG. 32 is a bottom view of the fourth part of the ball pit set thereof;
 FIG. 33 is a front perspective view of the fifth part of the ball pit set thereof;
 FIG. 34 is a bottom perspective view of the fifth part of the ball pit set thereof;
 FIG. 35 is a front view of the fifth part of the ball pit set thereof;
 FIG. 36 is a rear view of the fifth part of the ball pit set thereof;
 FIG. 37 is a left side view of the fifth part of the ball pit set thereof;
 FIG. 38 is a right side view of the fifth part of the ball pit set thereof;
 FIG. 39 is a top view of the fifth part of the ball pit set thereof;
 FIG. 40 is a bottom view of the fifth part of the ball pit set thereof;
 FIG. 41 is a front perspective view of the sixth part of the ball pit set thereof;
 FIG. 42 is a bottom perspective view of the sixth part of the ball pit set thereof;
 FIG. 43 is a front view of the sixth part of the ball pit set thereof;
 FIG. 44 is a rear view of the sixth part of the ball pit set thereof;
 FIG. 45 is a left side view of the sixth part of the ball pit set thereof;
 FIG. 46 is a right side view of the sixth part of the ball pit set thereof;
 FIG. 47 is a top view of the sixth part of the ball pit set thereof;
 FIG. 48 is a bottom view of the sixth part of the ball pit set thereof;
 FIG. 49 is a perspective view of the ball pit set;

FIG. 50 is a perspective view of the ball pit set in an alternate configuration;
 FIG. 51 is a perspective view of the ball pit set in an alternate configuration;
 FIG. 52 is a perspective view of the ball pit set in an alternate configuration;
 FIG. 53 is a perspective view of the ball pit set in an alternate configuration; and,
 FIG. 54 is a perspective view of the ball pit set in an alternate configuration.
 The claim is directed to the collective appearance of the ball pit set shown in the figures. The component of the set are arranged on the drawing sheet for the convenience of illustration, and the relative positioning of the ball pit set forms no part of the claimed design.
